Primary Examiner — Rosemary K Tarcza(74) *Attorney, Agent, or Firm* — JCIPRNET(57) **CLAIM**

The ornamental design for a wireless charger for portable terminal, as shown and described.

DESCRIPTION

FIG. 1 is a perspective view of a wireless charger for portable terminal showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof, shown in an environment of use with a portable terminal.

The broken lines showing of a portable terminal in FIG. 8 are for the purpose of illustrating environmental structure and form no part of the claimed design.
